UNITED STATES PATENT OFFICE.

CHARLES F. GROSSER, OF MINNEAPOLIS, MINNESOTA.

LEVEL.

No. 800,739.

Specification of Letters Patent.

Patented Oct. 3, 1905.

Application filed December 8, 1904. Serial No. 235,918.

To all whom it may concern:

Be it known that I, CHARLES F. GROSSER, a citizen of the United States, residing at Minneapolis, in the county of Hennepin and State 5 of Minnesota, have invented certain new and useful Improvements in Levels; and I do hereby declare the following to be a full, clear, and exact description of the invention, such as will enable others skilled in the art to which 10 it appertains to make and use the same.

My invention relates to levels, and has for its object to simplify and generally improve the same.

To the above ends the invention consists of 15 the novel devices and combinations of devices hereinafter described, and defined in the claims.

In the accompanying drawings, which illustrate my invention, like characters indicate 20 like parts throughout the several views.

Figure 1 is a view in side elevation with some parts broken away, showing a level designed in accordance with my invention. Fig. 2 is a section on the line $x^2 x^2$ of Fig. 1. Fig. 25 3 is a view corresponding to Fig. 1, but illustrating a slightly-modified construction; and Fig. 4 is a section on the line $x^4 x^4$ of Fig. 3.

The numeral 1 indicates the body of the level, which is recessed at its central portion 30 to afford a seat 2 for the transparent bulb or bubble-chamber. In the construction illustrated in Figs. 1 to 4, inclusive, the bubble-chamber is in the form of a hollow glass disk 35 3, which is round in circumference and double convex in cross-section. In the arrangement illustrated in Fig. 1 the sides of the bubble-

chamber 3, except at its peripheral portions, are covered by light metallic disks 4, which in turn are rigidly connected by radial arms 5 to the seat 2. The metallic disks 4 are 40 graduated at their margins to indicate degrees. In the construction illustrated in Figs. 3 and 4 the metallic disks are dispensed with. The bubble-chamber 3 is seated directly in an annular frame 6, and the degree-graduations 45 are marked directly on said frame 6. The bubble-chambers 3 are so nearly filled with alcohol or some other suitable liquid that only a small air-bubble z is left therein for coöperation with the degree-graduations to 50 indicate the angle at which the level is set.

What I claim, and desire to secure by Letters Patent of the United States, is as follows:

1. A level having a bubble-chamber, the periphery of which extends on the line of a 55 complete circle, and which is double convex in transverse cross-section, substantially as described.

2. A level having interposed in its body portion, a transparent bubble-chamber 3, the 60 periphery of which extends on the line of a complete circle and which in transverse cross-section is double convex, and a graduated annular scale surrounding said bubble-chamber and serving to hold the same in working position, substantially as described.

In testimony whereof I affix my signature in presence of two witnesses.

CHARLES F. GROSSER.

Witnesses:
